US00D719541S

(12) **United States Design Patent**
Lee et al.

(10) **Patent No.:** US D719,541 S
(45) **Date of Patent:** ** Dec. 16, 2014

(54) **MOBILE PHONE**

(71) Applicant: **Samsung Display Co., Ltd.**, Yongin-si, Gyeonggi-do (KR)

(72) Inventors: **Yong-Joon Lee**, Yongin (KR); **Woo-Jong Lee**, Yongin (KR)

(73) Assignee: **Samsung Display Co., Ltd.**, Yongin-si (KR)

(**) Term: **14 Years**

(21) Appl. No.: **29/448,444**

(22) Filed: **Mar. 12, 2013**

(30) **Foreign Application Priority Data**

Nov. 9, 2012 (KR) 30-2012-0053717

(51) **LOC (10) Cl.** 14-03

(52) **U.S. Cl.**

USPC ..... **D14/138 AB; D14/345**
